UNITED STATES PATENT OFFICE.

JOHN A. WHITTINGTON, OF ATLANTA, GEORGIA.

CHROMATIC CHASE FOR PRINTING PRESSES.

Application filed December 8, 1921. Serial No. 520,778.

To all whom it may concern:

Be it known that I, JOHN A. WHITTINGTON, a citizen of the United States of America, and a resident of Atlanta, State of Georgia, have invented certain new and useful Chromatic Chases for Printing Presses, the principles of which are set forth in the following specification and accompanying drawings, which disclose the form of the invention which I now consider to be the best of the various forms in which the principles of the invention may be embodied.

This invention relates to chromatic printing devices, and consists of various improvements on the printing chase disclosed in my Patent No. 1,292,190, dated January 21, 1919.

This entire chase is adapted as to its principal elements to be set in place alongside or in the midst of the usual type chases in the various types of printing presses, without alteration of the construction or operation of the press itself for which the chase may be particularly designed.

The general object of the present invention is to make more nearly perfect the color-printing chase of my said prior patent, including a reduction of the number of parts, movable and stationary.

As in my said prior patent, the chase includes, among other features, an oscillating support for type which is provided with a fountain for inking it a different color from the rest of the type in the press, the latter being usually black. The chase preferably also includes, as before, a support for type which is inked by the inking roller of the press.

One of the objects of the invention is the provision of improved means for tripping or operating the oscillating support for the color-type, and providing for yielding action in said means.

Another object is the provision of improved means for removably mounting separate type characters on the type supports.

Another object is the provision of improved means for mounting the black-type support in the chase and providing for the convenient removal and replacement of such support.

Another object is the provision of improved means for mounting the color-inking means within the chase, for moving it from the color-type before the latter is moved to printing position, and toward the color-

type after the latter has been moved to its normal inking position.

With the foregoing and other objects in view, which will be apparent as the description proceeds, the invention resides in the construction and arrangement of parts hereinafter described and claimed.

Of the drawings,

Figure 1 is a plan of the chase (somewhat smaller than actual size), showing the oscillating color-type 49 as having been swung (by the operation of the impression surface of the printing press of which it is to form a part) into printing position in the plane of black type 27 of the chase;

Fig. 2 is a like plan, but with color-type 49 in normal or inking position (at right angles to its printing position of Fig. 1) and with the black type 27 of Fig. 1 removed from the device in order to show the color-ink fountain 76;

Fig. 3 is a plan like Fig. 2 but with the ink fountain 76 removed, and showing its oscillating supporting plate 84;

Fig. 4 is a side elevation, with the right-hand one of the two outside boxing members 21 removed to show the construction of the principal elements including the main frame 14 and the tripping frame 17, the latter being a part which is operated by the impression surface of the press to swing the oscillating color-type to printing position;

Fig. 5 is a slightly enlarged right end view of the chase of Fig. 4 with one box member 21 removed, showing in section one of the two tripping levers 56 which are located at opposite ends of the device and which operate between the oscillating color-type 49 and its tripper frame 17;

Fig. 6 is an enlarged end view like Fig. 5 but with the tripping lever 56 thereof entirely removed from its connection with shaft 39 which carries oscillating color-type 49;

Fig. 7 is an enlarged cross section on line 7-7 of Fig. 4, showing the seating of black type 27 in the chase, and showing also the equalizing levers 71 which keep tripper-frame 17 level, the latter being shown in all the figures as the element which is operated by the impression surface of the printing press to swing the color type into its printing position of Fig. 1;

Fig. 8 is an enlarged cross section on line 8-8 of Fig. 2, showing black type 27 of the chase in fixed printing position and showing

swinging color-type 49 in inking relation with the color-inking means;

Fig. 9 is a portion of a longitudinal section on line 9—9 of Fig. 6 (compare Fig. 4), showing the interrelated construction of the principal elements of the chase, which construction is duplicated at the two ends of the chase; and

Fig. 10 is a cross section of the ink-fountain 76 with inking pad 78.

For clearness, Figs. 1—9 have been made to correspond with the figures of my said prior patent.

The stationary main frame or body of the device comprises a base or bottom plate 14 (Fig. 4) inside the two box-members 21 and having vertical flanges 15 extending longitudinally of the chase and along the side edges thereof. Base 14 also has vertical flanges 16 extending transversely of the chase; these flanges 16 being located near to and spaced from the ends of said base 14 (Figs. 4 and 9). As shown (Figs. 1—3), base 14 is of rectangular form, but may be of other shape. This base 14 with its vertical flanges 15 and 16 constitutes a main frame which supports the entire apparatus of the chase including the lateral boxing members 21 which constitute the sides of the chase.

A tripping frame or tripper 17 (Figs. 1—9) of the same shape as base 14 fits telescopically over vertical transverse flanges 16 of base 14. Said tripper 17 has vertically depending transverse flanges 18 (Figs. 6 and 9) near its ends which slidably overlap the outer sides of flanges 16 of base 14. The ends of rectangular tripper 17 (Fig. 9) project beyond its vertical depending flanges 18, and are provided with downwardly facing shoulders 19 extending to the inner wall of box 21. Tripper 17 is thus slidable on main frame 14 upwardly and downwardly, inside box 21. The top surface of tripper 17 may carry any suitable means for making a black-ink impression on the sheet to be printed. Thus, as shown (Figs. 1—3, 6—9), tripper 17, in the form of a four-sided frame, has a border portion 20 which will print any suitable block border around the impression made by the black and the color type of the chase, and may have means for holding removable type or may have lettering cut in it or electrotype supported on it.

Main frame 14, and tripper 17 above it, are encased by a pair of U-shaped boxing members 21 (Figs. 1, 3, 4, 6, 7, 9) fitting base 14 from the opposite ends. The ends of members 21 (Figs. 1 and 4) abut one another at opposite sides of the chase intermediate its ends, and are secured to vertical longitudinal flanges 15 of main frame 14 by screws 22. The ends of frame-base 14 may have pins 23 (Fig. 5) to engage the box-members 21 and assist in holding them in

position. Said members 21 thus provide a box or lateral wall within which tripping frame 17 is vertically reciprocal on main frame 14; and said box or casing also encloses the working parts mounted on main frame 14 at the sides and ends of the chase.

The main frame, with its base 14 and vertical flanges, carries the stationary or black type (shown in lower part of Fig. 1, and located above the color-inking means, Figs. 1 and 2). A type support 24 is mounted on transverse flanges 16 of base 14 (Fig. 7, line 7—7 of Fig. 4). Type support 24 extends longitudinally of the chase to carry the black type 27 (Fig. 1). The flanges 16 are provided with recesses 25 in their upper edges which receive the ends of longitudinal type support 24. Support 24 (Figs. 1, 7, 8 and 9) can have suitable type thereon, as an electrotype or cut, but, as shown, it is provided with means for receiving separately removable type characters 27, as follows. Support 24 has longitudinal slots 26 (Figs. 1 and 8) of inverted T-shaped cross section, and the type characters 27 (Figs. 8 and 9) have corresponding T-shaped lugs 28 which slide in said slots 26 into locking position in support 24. Slots 26 have openings 29 (Figs. 1 and 9) at one end to permit insertion and removal of the separate type characters 27, whereby various words can be set up as desired, and the printing by the chase can be altered from time to time. Support 24 also is removable as shown, so that it can be removed and replaced by another plate of the same shape but carrying a different type make-up or having an electrotype or cut thereon as disclosed in my said prior patent. In order to removably secure support 24 in place, its ends are seated in recesses 25 (Figs. 1, 7, 8 and 9) in transverse flanges 16 of main frame 14. The sides of support 24 are beveled at 31 (Figs. 7 and 8). One end of each recess 25 in transverse flange 16 of main frame 14 is provided with an undercut bevel 30, adapted to receive bevel 31 of support 24. A catch 33 (Figs. 2, 7 and 8) is provided (one at each end of support 24) at the right-hand end of recess 25 (Fig. 7). Catch 33 engages the side of support 24 opposite to its beveled side 30, and holds support 24 down in place. Each transverse flange 16 of main frame 14 has a slot 32 (Figs. 2 and 7), which intersects the end of recess 25, as shown. Catch 33 is located in this slot 32, the catch being pivoted by pin 34 (Fig. 7) extending through flange 16. Catch 33 has a V-shaped ear 35 (Figs. 2, 7 and 8) projecting to snap over bevel 31 of plate 24. A spring 37 forces ear 35 against bevel 31 (the spring being seated in a hole 36, Fig. 7, drilled into flange 16 of main frame 14). Ear 35 is beveled at top and bottom as shown. Said spring 37 per-

100
105
110
115
120
125
130

mits said ear 35 to yield in snapping support 24 in or out of position in recesses 25 of flanges 16 of frame 14. When the left-hand beveled side 31 of support 24 is inserted under bevel 30 (Figs. 7 and 8) and the right side of support 24 is pressed down, said right side in pressing down on the upper bevel of ear 35 will tilt the right-hand side of catch 33 down. Thereupon the bevel 10 of the right side of support 24 will engage under the lower bevel of ear 35, and force the right-hand part of catch 33 down against spring 37 into the locking position of Fig. 7, where the left-hand portion of 15 the catch is in engagement with the lower part of support 24. Reverse operation permits removal of support 24 with equal facility, if desired to replace support 24 or to obtain access to the color-inking means below it. Catches 33 are contained within recesses 32 of transverse flanges 16, thereby providing a compact and efficient arrangement (Figs. 1 and 7).

Oscillating color-type bar or carrier 38 (Figs. 2, 3 and 8) is disposed longitudinally of the chase alongside support 24 for black type 27 (Fig. 1). It carries type which can be inked in red or other color, character or composition distinct or different from the 30 rest of the type in the chase and in the rest of the printing press, both of which are usually inked in black. Carrier 38 has a swinging or oscillating movement transversely of the chase, being mounted on a rod 35 or shaft 39 (Fig. 8) extending longitudinally of the chase and journaled in vertical transverse flanges 16 of main frame 14. Carrier 38 is pinned to shaft 39 to oscillate therewith. Its intermediate portion is recessed, as at 40 (Fig. 8), to receive a spring 41 coiled around shaft 39. Upper end 42 of spring 41 engages carrier 38 and lower end 43 is located in longitudinal flange 15 of main frame 14. Thereby spring 41 tends 45 to swing carrier 38 to its normal or inking position shown in Figs. 2, 3 and 8, and holds it in that position save when said carrier is swung to and held in its printing position of Fig. 1.

Carrier 38 carries a color-type holder 45 (Figs. 1-3 and 8). Holder 45 may be a die-casting, and removable for changing the type or substituting another holder. Holder 45 has a portion 46 (Fig. 8) fitting a longitudinal groove 47 in the face of carrier 38. Set screws 48 carried by carrier 38 clamp rib 46 of holder 45 in groove 47. Said screws 48 when loosened permit holder 45 to be removed. Holder 45 has separate removable type characters 49 therein (Figs. 1-3 and 8), although it may have an electro-type or cut thereon. Type characters 49 have T-shaped lugs 50 (Fig. 8) which slide longitudinally in a groove 51 in holder 45. The ends of holder 45 and its slot 51 extend

to vertical transverse flanges 16 of main frame 14 (Figs. 1-3) so that said flanges 16 normally close the ends of said groove 51 in holder 45 and hold the type in place. When holder 45 is removed from carrier 38, the ends of groove 51 are opened, and the color-type characters 49 can be readily slid into and out of said groove through the ends thereof, thus enabling the words or characters in holder 45 to be changed at will. Carrier 38 has buffers 52 (Figs. 1-3 and 8) to strike the inside wall of tripping frame 17 (Fig. 8) when the carrier is swung to the printing position of Fig. 1. Stops 44 locate carrier 38 in its inking position. Of course, any suitable printers' devices can be used to hold the type in the desired position in its line.

The construction for swinging the carrier 38 of color-type 49 from its inking position of Fig. 8 to its printing position of Fig. 1 is as follows. Two disks 53 (Fig. 6) are secured (keyed) to the opposite ends of oscillating shaft 39 on which carrier 38 is fixed for oscillation thereby. Flanges 18 vertically dependent from tripper frame 17 have recesses 55 receiving said disks 53. Disk 53 has a crank pin 54 mounted on it eccentrically and projecting outwardly from it. Shaft 39 is swung up to type printing position by depression of tripper 17 by engagement of the impression surface of the printing press with any of the four sides of the tripper 17 when in the form of a four-sided frame as shown. Shaft 39 is swung back to normal (inking) position by spring 41. Tripping levers 56 operate between tripper 17 and disks 53, and (Figs. 5 and 6) each lever 56 has an aperture 57 receiving crank pin 54 of the disk. Levers 56 are disposed at opposite ends of the chase just inside casing walls 21 (Figs. 9 and 5) and between said walls and vertical transverse flanges 18. The vertical disposition of levers 56 is between base-plate 14 (Fig. 9) and the overhanging shoulders 19 of tripper 17. Crank pin 54 on disk 53 is raised (Fig. 8) when carrier 38 is swung by spring 41 back to normal (inking) position, thereby raising the end of lever 56 which is engaged by pin 54 (Fig. 5), while the other end of lever 56 slides on base-plate 14. Pressure on lever 56 by downward movement of tripper 17 depresses pin 54, to turn shaft 39 and swing carrier 38 to printing position to bring color-type 49 into the plane of the black type 27 of plate 24 (Figs. 1 and 8). Each lever 56 has yieldable means thereon (springs 64, 65, Fig. 5) for compression by tripper 17 and involved in the following construction. Each of the two levers 56 (Figs. 5 and 9) has an upper longitudinal recess 58 receiving a pressure member 59. The latter is guided and limited in its upward movement in recess 58 by a pair of 130

screws 60 (Fig. 5) threaded downwardly into lever 56 and projecting above it. Pressure member 59 has apertures 61 near its ends receiving the headed ends of screws 60 to limit its upward motion. Pressure member 59 has sockets 62 below the screw-head apertures 61, and has two sockets 63 between the two sockets 62, and in these sockets 62 and 63 are seated the coiled expansion springs 64 and 65. Said springs are confined between pressure member 59 and lever 56 to tend alternately to resist and raise pressure member 59 with the desired force. Springs 64 and 65 also distribute the pressure between pressure member 59 and lever 56 throughout the length of the pressure member. The latter (59) has an opening 66 (Fig. 5) intermediate its ends, in which a plunger 67 is slideable upwardly and downwardly. A coiled expansion spring 68 is confined in a socket 69 in plunger 67. The upper end of plunger 67 has a head or flange 70 (Fig. 5) which seats on pressure member 59 and thereby limits the relative movement of plunger 67 and pressure member 59. Springs 68 raise plunger 67 to bring plunger-head 70 against shoulder 19 of tripper 17 (Figs. 5 and 9). With this arrangement (Fig. 5), pressure member 59 is raised by considerable pressure from springs 64, 65. But the upward movement of pressure member 59 is limited by the heads of screws 60 in lever 56. The two plungers 67 (at opposite ends of the chase) in being raised by the light springs 68, will raise tripper 17 to its normal lifting position above level of black type 27, in the path of the impression surface of the printing press. Thus, during the first movement of tripper 17 when depressed (Fig. 5) by the impression surface of the printing press, tripper-shoulders 19 (Fig. 9) will depress plungers 67 until their heads 70 seat on pressure member 59. Then the two pressure members 59 are depressed against springs 64 and 65. Thus, during the first part of the depression of the tripper 17, it acts only against plungers 67 and springs 68. But after heads 70 of plungers 67 seat on pressure members 59, the latter are depressed until the downward force exerted by springs 64, 65 on levers 56 is increased sufficiently to cause levers 56 to move down. This provides (Figs. 5 and 8) for a slight depression of tripper 17 before levers 56 are depressed to turn color-type carrier 38 to printing position; and this arrangement is utilized in connection with the operation of the color-inking mechanism to be described. Furthermore, the mounting of pressure members 59 on levers 56 (Figs. 5 and 8) provides for yieldingly imparting the pressure from plungers 67 to levers 56. When levers 56 are depressed, they carry with them the crank pins 54 which turn

disks 53 and shaft 39 and swing color-type bar 38 to printing position.

Means are provided to compel tripper 17 to move downwardly and upwardly in a level plane, thereby preventing an uneven or tilting position of the tripper when one of its frame sides is engaged by the impression surface (as a cylinder) of the printing press. A pair of levers 71 is located at each end of the chase (Figs. 6, 7 and 9). Each pair is located in the vertical space (Fig. 9) between a vertical transverse flange 16 of the main frame and a vertical transverse flange 18 of the tripper 17. Levers 71 are placed below an overhanging shoulder 73 of flange 16 (Figs. 9 and 5). Each lever 71 of each pair is fulcrumed at 72 (Fig. 7) intermediate its ends and to flange 16. The adjacent ends of the two levers 71 which project toward one another have intermeshing teeth 74 (Fig. 7), which constrain the two levers to swing simultaneously on their pivots 72. Levers 71 are arranged to be swung by downward movement of tripper 17; the ends of levers 71 being connected by pins 75 to flange 18 of the tripper (Figs. 5, 6 and 7). Thus, when the impression cylinder of the press engages one side of tripper frame 17, the end of lever 71 next to that side is depressed by the downward movement of the tripper, and such swinging of such lever 71 causes its engaging lever 71 to swing and thereby pull down the opposite side of tripper 17, so that the entire tripper frame is kept level in its downward movement; and likewise when, later on, the tripper is moved upwardly to its normal position above type level. The pins 75, which are screwed in tripper 17 and enter lever 71 (Figs. 6 and 7), hold tripper 17 against removal, owing to the location of levers 71 below shoulders 73 of vertical transverse flange 16 of the main frame; although, for making repairs, the removal of screws 75 will permit tripper 17 to be lifted out of the chase.

The means for supplying colored (red) ink to oscillating color type 49 includes an elongated ink fountain or reservoir 76 (Figs. 2, 8, 9 and 10) disposed longitudinally of the chase below black type holder 24 (Figs. 8 and 9). The long side of fountain 76 which is nearest to oscillating type-carrier 38 (Fig. 8) has a longitudinal channel 77 holding an ink pad 78, preferably composed of felt (Fig. 10). The partition between fountain 76 and pad 78 has apertures 79 which permit the passage of ink from fountain 76 to the pad 78 from which the ink passes to color type 49 when bearing against the type as in Fig. 8. Fountain 76 has an upper filling opening 80 (Fig. 10). A stopper 83 snaps into opening 80 to close it (Figs. 10 and 2). Stopper 83 is carried at the end of spring arm 81 pivoted at

82 to the top of fountain 76. The fountain is filled by removal of black type support 24 above fountain 76 and removal of stopper 83.

5 The entire inking mechanism is mounted for swinging movement in a support 84 (Figs. 8 and 2). The long side of support 84 which lies adjacent to type-carrier 38 (Fig. 8) is pivoted on a rod 85 extending longitudinally of the chase. Support 84 is shown as a sheet metal stamping and is bent around rod 85 at 86. Rod 85 has its ends secured in the two end flanges 16 of the main frame (Fig. 9). The opposite site or swinging side of support 84 (Fig. 8) has a flange 87 bent upwardly to assist in holding fountain 76 in place (Figs. 2, 3 and 8). When support 84 swings upward on its pivot 85, pad 78 is swung toward oscillating carrier 38 and color type 49 thereon. When support 84 is swung downward on 85, the pad 78 is swung away from type 49. Support 84 has posts 88 extending upward vertically from its opposite ends (Figs. 2, 3 and 8). These posts also assist in holding fountain 76 in place. The ends of channel 77 holding pad 78 project longitudinally of the chase and beyond the ends of fountain 76 and bear against posts 88 to further assist in holding the inking mechanism in support 84. The ends of fountain 76 have pins projecting therefrom (Figs. 2 and 8) which extend to one side of posts 88, so that said posts rise between pins 89 and channel 77. Thus the fountain and pad structure of Fig. 10 may be put in place on its support 84, and removed therefrom, by the guiding of pins 89 and channel 77 on opposite sides of support posts 88.

40 The above inker is moved toward oscillating color type 49 by two springs 90 which engage the sides of the inker near opposite ends thereof (Figs. 2, 3 and 8). Each spring 90 is confined between posts 88 of fountain support 84 and posts 91 secured to the main frame 14 as by screws 92 (Figs. 8 and 4). Said spring-supporting posts 88 and 91 have studs 93 which enter in the end of spring 90 and position the springs. Normally, these springs 90 hold pads 78 against color type 49. In the movement of the inker toward the color-type, the posts 88 bear against channel 77 (Figs. 2 and 8).

45 The inker is positively swung against springs 90, away from color type 49 by the initial depression of tripper 17, and in such way as to avoid swinging of type 49 while engaged by pad 78, as follows. Pins 94 project from posts 84 at the ends of the inker (Fig. 8). These pins 94 project through openings in vertical transverse end flanges 16 of the main frame, and also through openings 95 in equalizing levers 71 (Figs. 4, 6 and 7). Pins 94 project into

50 recesses or slots 96 in vertically-depend ing flanges 18 of tripper 17 (Fig. 6). Said recesses 96 are enlarged at the bottom of the tripper flange, to form shoulder-corners 97 which normally bear on pins 94 (Fig. 70 6). The pins 94 normally engage the corner of shoulder 97 so that as soon as tripper 17 (Fig. 6) begins to move downward, pins 94 are forced to the left (Fig. 6) against springs 90 (Fig. 8). The continued downward movement of the tripper results in recess 96 coming down around pins 94 without causing further movement of said pins. But the initial movement of the tripper, moving pins 94, has moved posts 88 to which 75 they are secured and has swung support 84, thereby swinging fountain 76 and pad 78 away from color type 49. This operation is permitted while (Fig. 5) tripper 17 is depressing plungers 67 and before the heads 80 of thereof have engaged pressure members 59. Type-carrier 38 is not started swinging to printing position until heads 70 of plungers 67 have engaged pressure members 59, which is after the inker has been swung 85 away from the color type as described. The above construction and arrangement provides for a quick withdrawal of pad 78 from type 49 during the initial depressing of tripper 17 and before type carrier 38 is 90 started in its swing toward printing position by the depression of pressure members 59 and levers 56.

95 The inker hereof is particularly designed for a chase adapted for use with reciprocating flat bed presses in which the bed reciprocates at a rate from a few hundreds to several thousands per hour. The color ink used is preferably heavy, and the high speed of the bed is usefully employed in assisting the heavy ink to pass out through upper holes 79 of fountain 76 to the pad, even when there is only a small quantity of ink left in the fountain. It appears also as if the pressing of the felt pad on the color type moved the fibers of the pad so as to assist the capillary action and the movement of the press bed in bringing out the heavy ink from the fountain and through the pad to the type, i. e., a sort of kneading or milking action of the pad by the color-type. Preferably, in making the ink pad, the felt should be cut so that the grain of the wool is at right angles to the color type, so that such fibers may act as multiple wicks or teats.

100 The various parts of the chase shown herein to which detailed reference has not been made may follow in general the chase of my said prior patent. In any design embodying my inventions in this chase, the tripper should be permitted to move down as easily as possible without being permitted to be depressed by the inking roller of the press to cause unnecessary operations at the 105 110 115 120 125 130

high speed of printing press operation involved; and to this end the springs should be easy and there should be as little friction of moving parts as far as convenient. Such ease of motion of the tripper is important in that it reduces the printing indentations on the paper by the tripper, which should not be deep enough to show on the back of the paper; for generally the tripper frame 10 is black printer as well as a tripper.

The operation of the chase as a whole is as follows. When the chase is traversed by the inking roller of the press in which it is used, such roller, being made as usual of a yielding composition, will yield at points where it engages with (and inks) the bordering sides 20 or other printing surfaces of the tripper 17 (Figs. 1-3, 7-9). This yielding is preferably sufficient to prevent 20 operation of any of the parts of the chase, that is, the design of the chase is preferably such that the tripper will not be moved by the inking roller (but only by the rigid impression surface of the press) even to the 25 extent of withdrawing the inker from the color type as above described, although such action may be permitted. If such action is permitted, there will be two color-inking actions for each color-printing operation, 30 due to the fact that the inking roller of the press will leave the tripper before the latter is depressed by the rigid impression surface of the press which operates tripper 17.

The resistance of springs 64, 65, 68 and 35 41 (and the general inertia and friction of the various parts) may be made sufficient, in combination with the yielding material of the inking roller, to prevent any depression of the tripper by the roller, especially 40 in view of the short extent of projection shown herein of the tripper normally above type level, with or without sufficient additional rigidity of springs 68 of plunger 67 (Fig. 5.) The movement of the inking roller, however, at least will apply the ordinary black ink of the press to any printing surfaces carried by tripper frame 17, and to any other black-printing surfaces of 45 the chase such as type 27, in common with 50 the like black-inking of the type in the other parts of the press in which my chase is used. When the sheet of paper to receive the printing impression is pressed against the chase by the rigid impression cylinder or platen of the press carrying said paper, tripper 17 will be depressed by the substantially unyielding impression surface of such cylinder or platen.

Thereupon the general operation is as follows. 60 (1) Ink fountain 76 and pad 78 are withdrawn from color type 49 while the latter is at rest in its normal vertical position (Fig. 8), the inker being entirely removed from the circular path of swinging movement of the color type before the lat-

ter is started in its oscillation to and from printing position. (2) Then type 49 is swung toward horizontal printing position, a part of it moving first across the space just previously occupied by pad 78, and then an opposite corner of it moving across the path (above type level of the press) of the impression surface of the press (Fig. 8), and finally into ultimate printing position at rest in advance of the arrival of the impression surface at such position. (3) Then tripper 17 continues its downward movement until (all in a very short time indeed) it has been fully depressed by the impression surface, this continued movement of the tripper after the color type has reached printing position being permitted by the spring arrangement described. (4) Then the impression surface of the press 35 passes over the space within the four sides of tripper 17 including all the printing surfaces thereon, and the impressions thereof, of black type 27 and of color type 49 are printed on the paper carried by the impression surface. (5) Then the impression surface leaves the tripper frame, whereupon spring 41 retracts type 49 to its normal (inking) position, the tripper also being started toward its normal elevated position 95 above type level, the inking pad being held from movement toward the color-type. (6) Tripper 17 continues its upward movement and just as it reaches normal position, ink pad 78 is swung against color type 49 but only just after the latter has reached its 100 position of rest.

During all of these six operations, the equalizing levers 71 (Fig. 7) have been functioning to keep tripper frame 17 level 105 irrespective of its changing relations with the impression surface of the press, so that there is no tilting or jamming of said frame 17 as the impression surface traverses the frame from one side or end to the other 110 side or end.

The details of the above six operations are as follows.

(1) During the initial downward movement of tripper 17 (which effects the withdrawal of the inker from the color type 49), plungers 67 (Fig. 5) are depressed against their springs 68 without starting oscillation of the color type, i. e., without moving pressure members 59 or levers 56 which swing the color type. This initial downward movement of the tripper is down to the point where the heads 70 of plungers 67 reach pressure members 59. Meanwhile pad 78 is swung away from the color type 125 and out of its path of forthcoming swinging movement, by way of the depression of the left-hand end of fountain-carrier 84 (Fig. 8). This latter is effected, as described, by corners or angles 97 of vertical 130

flanges 18 of tripper 17 (Fig. 6), which move pins 94, mounted on support or carrier 84 (Fig. 8), so that the latter is swung down on its hinge 86. The inker is held in this retracted position during the further depression of tripper 17 and until the latter, after the printing operation, is moved back toward its normal position. This maintenance of the inker in its withdrawn position is effected by the holding of pins 94 in tripper-slot 96 and by slide 98 to be described (Fig. 6).

(2) Immediately after the withdrawal of the inker from color type 49, the latter is swung upward with its pivot-shaft 39 by the engagement of heads 70 of plungers 67 with pressure members 59. The latter thereby are depressed against their springs 64, 65. At any desired time after the beginning of downward movement of members 59 (depending on the rigidity of springs 64, 65, Fig. 5, which cushion the blow of the impression surface on the tripper), the downward movement commences of the right-hand ends of levers 56 and of crank pins 54 (Fig. 6), whereby type-carrier 38 is swung against its spring 41 to move color type 49 to its position of rest in the printing location of the type at type level of the press (Fig. 1). In this operation, the downward movement of tripper 17 is amplified (permissively several times) by the mechanical lever arm which exists between crank pins 54 and the points of engagement of the tripper with plungers 67. Normally, crank pins 54 (Fig. 6) are at an angle of about fifty degrees above horizontal; but in the swing to printing position they are moved through an angle of ninety degrees. This amplifying arrangement is similar in this respect to that of the levers 27 of the chase of my said prior patent.

(3) Then follows the complete depression of tripper 17 by the previously-commenced engagement of the impression surface of the press with a side or end of the frame of the tripper itself. This acts against springs 64, 65 and (or) spring 41, to hold color-type 49 at rest in its printing position and (by the provision of the lost motion) to ensure the color-type reaching a position of rest in printing position before the completion of the downward movement of the tripper.

(4) Then the impression surface of the press comes into printing relation with color type 49 while the latter is held at rest in printing position (Fig. 1).

(5) Then the impression surface leaves the chase. As soon as this occurs, tripper 17 is free to be moved back (together with levers 56) to its normal position extending above type level of the press, by means of the spring arrangement. Thus, spring 41 (Fig. 8) forces type-carrier 38 back to normal (inking) position and holds it at rest

thereat; also, via crank pin 54, the right-hand ends of levers 56 are moved upward by spring 41 (Figs. 8, 5), so that they are restored to normal position.

(6) The swinging of the color-inker against the color type at rest in inking position (Fig. 8) is effected as follows. Almost at the end of the upward movement of tripper 17, its shoulder-corners 97 (Fig. 6) are raised high enough to permit inker-springs 90 (Fig. 8) to force pins 94 into the bottom portion of slot 96 of the tripper (Fig. 6), whereby inking pad 78 is swung by springs 90 against color type 49 to the position of rest of the latter. The arrangement of shoulder-corners 97 is such that springs 90 are not permitted to move the inker until tripper 17 has substantially reached its normal elevated position. The construction may be such (as a suitable yielding composition of pad 78, or otherwise) that the chase will be operative even if, on return to normal relations of Fig. 6, the returning-springs cause the movement of the pad to a position of rest in its normal printer-inking location, prior to the swing-back of the color printer across part of the space occupied by the pad in such normal location. But positively-acting means may be provided, and preferably are provided, to ensure against premature action of said springs 90 (Fig. 8) in moving pad 78 to its inking position, i. e., to prevent such action until after color type 49 has been swung down beyond a point where it might make moving contact with the pad which might injure the inker or the type, or both. As type 49 is swung down, a corner of it will cross the space occupied by pad 78 when at rest in normal inking position. At first that corner of the type-member, in swinging through its arc, will move toward the pad, but at a certain point in its swing it will begin to move away from the pad, the latter movement being just before the type reaches its position of rest. Therefore it is desirable that the pad should not reach said point until the corner of the printer starts its movement toward final inking position and away from the pad, whereupon both the pad and said type corner move in the same general direction, i. e., toward their normal (inking) positions of Fig. 8. In order thus to hold the pad, springs 90 (Fig. 8) may be prevented from prematurely moving the pad to inking position. Slot 96 of tripper-flange 18 (Fig. 6) may be formed, as shown, between said flange itself and a sliding latch 98 supported by tongue 99 having freedom for lateral sliding motion in the slot shown in flange 18. Latch 98 is formed with a pivoted tooth 101 bearing against a flattened portion of the periphery of disk 53, and normally extending over tooth 102 of said disk and held down on latch 98 by the spring 103. In the

normal (inking) relations shown in Fig. 6, pin 94 is in position where it has moved pad 78 against color type 49 (Fig. 8) on the spring-return movement from the printing position of the color type. Upon the movement from normal (inking) relations to printing position, as tripper 17 is moved down by the impression surface of the press, pin 94, in being pushed to the left (Fig. 6), slides latch 98 and to the left, thereby withdrawing tooth 101 from shoulder 102; pivoted tooth 101 swinging upward against spring 103 to permit the slight downward component of the motion of latch 98. (This permits the above-described clockwise motion of crank-disk 53 and crank-pin 54.) After this action, tooth 101 is carried directly downward with tripper 17 and its flange 18 (tooth 101 departing entirely from contact with the periphery of oscillating disk 53 and being moved by spring 103 down to normal position). Later, upon the spring-return of all the parts to normal relations of Fig. 6, tripper 17 starts to pull up tooth 101 before pin 94 has passed to the right of corner 97; and meanwhile disk 53 is being swung counter clockwise to its normal position of Fig. 6. The result is that just as disk 53 and tripper 17 are coming to rest, and when pin 94 has passed under corner 97, teeth 101 and 102 come into their vertical relations shown in Fig. 6, so that pin 94 under impulsion of springs 90 (Fig. 8) forces latch 98 to the right and causes engagement of tooth 101 above tooth 102. Said motion of pin 94 to the right is that which carries pad 78 to its normal (inking) position; but that motion is not permitted while tooth 101 is prevented by the periphery of disk 53 from movement to the right (Fig. 6), for latch 98 is held in position to prevent pin 94 from moving to the right even if corner 97 of the tripper has been moved above the position of pin 94 in slot 96. The design is such that latch 98 is not permitted to move to the right until color type 49 has come to rest in inking position; the return movement of pad 78 taking place just at the instant that tripper 17 is reaching its normal position above type level and just as disk 53 is reaching its position of rest as shown. Thus it is made impossible for pad 78 to reach its inking position prior to the time that color type 49 has been swung thereto. Preferably the design of the parts shown is such that tooth 101 cannot be snapped over tooth 102 until the corner of type 49, which crosses the space occupied by pad 78 when in its inking position, has begun its movement away from and with the pad toward their inking positions.

By the above construction and arrangement, the oscillating color type is not permitted to be swung to or from the felt inking pad while these two members are in en-

gagement with one another, for such swinging movement on pivot-shaft 39 would cause type 49 to dig into and rub against the pad and result not only in injury to or undue wear on the pad and in the inking of the depressions in the type, but would also result in wear of the type itself. 70

The provisions in this improved chase whereby the operation of the tripper by the impression surface of the press alone controls all the operations of the chase, and whereby the color-inker, normally in contact with the color-printer, is moved away from it before the commencement of the swinging of the color-printer to printing position, and toward the color-printer after the latter has swung to rest in inking position, are of great practical importance in that they permit all the operations, including the inking and the oscillating of the color-printer, to be co-ordinated and timed for the best effect independently of the construction of the press itself, and also permit reduction in the number of moving parts. These features also prevent the drying of the inking pad (by its normal covering by type 49) and prevent wearing of pad and type by moving contact with one another. These features, therefore, are those of most marked improvement upon the chase of my said prior patent, wherein the color-inking was effected by the operation of the inking roller of the press in combination with a special movable arrangement of the black type of the chase, and wherein the best possible operation was not secured by a timely complete separation of the color-inker and color-printer. 95 100

The disclosed embodiment of the invention is designed particularly for use in printing presses employing a cylindrical impression surface, including reciprocating flat bed presses wherein separate sheets of paper are printed, and including also stationary flat bed presses of the web type wherein the paper is fed from a roll. In all such cases, the paper is printed while it is on an impression surface which is cylindrical. It is such cylinder which operates my chase upon its engagement with any one of the four top sides of tripper frame 17. 110 The disclosed embodiment is specially designed for such types of presses, by virtue of the design of the tripper in the form of the multi-sided frame 17 (or at least in a form having one or more of such sides), and by the provision of the equalizing devices 71 in combination with any such tripper form, and by the short height of tripper 17 above type level, and by the corresponding design involving the various resistances (including the spring arrangements) to the movement of the movable parts. The entire operation of swinging the oscillating color type to printing position is effected by the engagement of the impres- 115 120 125 130

sion cylinder of the press with one side of tripper frame 17. In this operation, a part of the color type swings above printing position across the path of the impression cylinder of the press. In the above-stated types of presses, there is time for the color type of my chase to be swung out of such path and to a condition of rest in printing position, prior to the instant when the impression cylinder reaches printing position over the chase. In fact, before the impression cylinder has reached the color type, it has not only swung the latter to printing position but thereafter has further depressed tripper 17 to further compress the springs. Thus the color type is brought to rest in printing position before the impression cylinder has reached it. I provide an extent of downward movement of tripper 17 which is a little more than necessary to bring the color type to printing position, in order to ensure that the color type shall be at rest in printing position and out of that part of its swing which crosses the path of the impression cylinder, before the latter has reached that point. In the use of my chase with the above-stated types of presses, there is no necessity for hurrying the color type to printing position (for the reason stated above), and therefore no need of any greater height of tripper 17 normally above type level than that shown. Furthermore, in those of the above-stated types of presses in which the impression cylinder is elevated between times of printing, such elevation is only a small fraction of an inch; therefore the disclosed short height of the tripper is advantageous in the use of the chase with such presses, in order to prevent contact with the impression cylinder, when the latter passes over printing position without being depressed for printing operation.

My invention, however, is useful, not only with the above types of presses, but also with job presses having a stationary bed and a flat impression surface or platen between which separate sheets of paper are printed, provided that tripper 17 is given such additional normal height above type level that the oscillating color type is given time to swing completely across and out of the path of the platen which is depressing the tripper, before the platen reaches the type, thereby preventing the type from being engaged by the paper on the platen while the type is in swinging transit toward but above its printing position. In cases of use with such flat platen presses, as well as in use with the other stated types, the spring arrangement should be designed so that after the color type has reached printing position, the tripper may continue to yield to the platen. But in the case of the job presses with movable flat platens, where the platen moves as a plane toward

the plane of the type, there will be no particular object in designing the tripper to have the frame form shown herein, or even to have one or more sides disposed horizontally above type level. In fact, as each such top side or edge itself prints at least a line or series of dots, any such frame form of the tripper might be positively undesirable in such cases, in which case the tripper may be designed to have any form or arrangement suitable for operation by such flat platen, as a single button or pair of small buttons having minimum printing surfaces or located outside of the area of the sheets of paper being printed. On the other hand, in any case of a press having a cylindrical impression surface, the design of the tripper in the form of frame 17 hereof is advantageous in that it permits the location of my chase in the bed irrespective of which side of such frame is first presented to the action of the impression cylinder; but in designing a form adapted to permit the impression cylinder to engage the side of the tripper frame which lies adjacent the swinging color-printer, care should be taken to allow ample distance between such tripper-side and the color-printer, so that the latter will have been swung out of the path of the cylinder before the latter reaches it.

When the tripper is in the form of a frame or extends over considerable area (more or less, as shown), there is no reason why it may not be designed to afford as much black-printing surface as desired without limitation to the edges 20 (Fig. 1) which are engaged by the impression surface. As a single illustration, it would be possible within my inventions to design the tripper-frame to extend through the space occupied herein by black-type holder 24 so that the tripper itself might carry the type (or an electrotype) now shown in holder 24; the tripper in such case, however, being entirely free as usual for its functional depression by the impression surface, and the type itself being so disposed that it will have reached its position of rest before the type carried by it is engaged by the impression surface. With such an arrangement, an advertiser can have an electrotype of standard wording for use on the tripper, surrounding the color-type, and the wording of the latter could be changed from time to time by the printer at the direction of the advertiser. In my type of chase, the location of the color-inker adjacent and parallel with the oscillating color-printer, provides a space above any inker of adequate capacity, which space most usefully can be utilized to contain type to be inked by the ink-roller of the press; and while I do not claim herein to be the originator of any features suggested in this paragraph, yet I consider that any such modifications are

within the scope of my inventions of my type of chase.

Furthermore, there are various features of my inventions which are not limited to combination with various other features, notwithstanding that in a given embodiment, one of such features may be usefully cooperative with another of such features. As an example of this, the inking surface 10 of the color-inker need not be in the form of a non-rotating pad, but might comprise an inking roll constructed and arranged in a manner similar to that of the inking roll of the press itself. Many other departures 15 may be made within the scope of my inventions, not only as to details but also as to principal features, from the particular embodiment shown herein; and while I do not herein claim originality for any such modifications, yet many of them may be within the scope of my inventions and therefore my claims are intended to be interpreted accordingly.

I claim:—

- 25 1. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 30 type level in the path of the impression surface of the press; connecting means with the tripper whereby its initial downward movement moves the color-inker away from the printer; and connecting means whereby the further downward movement of the 35 tripper moves the printer to printing position.
- 40 2. A chromatic chase for printing presses which comprises a main frame; a color-printer mounted in said frame to oscillate to and fro through a quarter-revolution from a normal vertical inking position to a horizontal printing position at type level of the press; a color-inker mounted in said frame adjacent the color-printer and movable from normal position in contact with 45 said printer; a tripper mounted in said frame and normally projecting above the same and above type level in the path of the impression surface of the press; connecting means between the tripper and the color-inker and arranged to cause depression of the tripper to move the inker away from the printer; and connecting means between the tripper and color-printer and arranged to cause the depression of the tripper to swing the printer from inking to 55 printing position.
- 50 3. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 55 type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.
- 60 4. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 65 type level in the path of the impression surface of the press; connecting means with the tripper whereby its initial downward movement moves the color-inker away from the printer; and connecting means whereby the further downward movement of the tripper moves the printer to printing position.
- 65 5. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 70 type level in the path of the impression surface of the press; and mechanism constructed and arranged to cause, successively, upon the depression of the tripper, the movement of the inker away from the printer and the swinging of the printer to printing position, and to cause, upon withdrawal of the depressing force on the tripper, the successive return of printer and inker to normal positions.
- 75 6. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from 80 normal position in contact therewith; a tripper constructed normally to project above type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

70 3. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 75 type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

80 4. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 85 type level in the path of the impression surface of the press; connecting means with the tripper whereby its initial downward movement moves the color-inker away from the printer; and connecting means whereby the further downward movement of the tripper moves the printer to printing position.

90 5. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from normal position in contact therewith; a tripper constructed normally to project above 95 type level in the path of the impression surface of the press; and mechanism constructed and arranged to cause, successively, upon the depression of the tripper, the movement of the inker away from the printer and the swinging of the printer to printing position, and to cause, upon withdrawal of the depressing force on the tripper, the successive return of printer and inker to normal positions.

100 6. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from 105 normal position in contact therewith; a tripper constructed normally to project above type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

110 65 7. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from 115 normal position in contact therewith; a tripper constructed normally to project above type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

120 8. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from 125 normal position in contact therewith; a tripper constructed normally to project above type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

130 9. A chromatic chase for printing presses which comprises a color-printer mounted to oscillate to and fro through a quarter-revolution from a normal vertical inking position below type level of the press to a horizontal printing position at type level; a color-inker located adjacent the color-printer and mounted to be movable from 130 normal position in contact therewith; a tripper constructed normally to project above type level in the path of the impression surface of the press; and mechanism connected between the tripper on one hand and the printer and inker on the other, and arranged to cause, successively, upon the depression of the tripper, the movement of the inker away from the printer, and the swinging of the printer to printing position.

- normal position in contact therewith; a tripper constructed normally to project above type level in the path of the impression surface of the press; springs arranged to tend 5 to hold the printer and inker in their normal inking relation; and mechanism operated by the depression of the tripper to move the inker and printer successively from their inking positions, said mechanism 10 and said springs being arranged to cause such movement to store energy in said springs, and to cause the springs to operate the mechanism to return the printer and inker successively to their inking positions.
- 15 7. A chromatic chase for printing machines which comprises a color-inker located below type level, and mounted to be movable from a normal (inking) position; a color-printer pivoted adjacent the color-inker to 20 be oscillated from normal (inking) position in contact with the inker to printing position and back to inking position; a tripper mounted to be reciprocable from and to normal position above type level of the press in 25 the path of the impression surface thereof; mechanism connected with the color-inker and constructed and arranged to be operated by the initial movement of the tripper from normal (high) position to move the inker 30 from normal (inking) position, and during the final return movement of the tripper to normal (high) position to effect the return of the inker to normal (inking) position and tend to hold it thereat; and mechanism 35 connected with the color-printer and constructed and arranged to be operated by the continued movement of the tripper toward abnormal (low) position after the movement of the inker from inking position, to swing 40 the printer from normal (inking) position to printing position and during the movement of the tripper from abnormal (low) position to swing the printer back from printing position to normal (inking) position and tend 45 to hold it thereat.
8. A chromatic chase for printing machines, which comprises a color-inker located below type level, and mounted to be movable from and to normal (inking) position 50 below type level; a color-printer pivoted adjacent the color-inker to be oscillated from normal (inking) position to printing position and back to inking position; a tripper mounted to be reciprocable from and to normal 55 position above type level of the press in the path of the impression surface thereof; mechanism constructed and arranged to be operated by the initial downward movement of the tripper from normal (high) 60 position to move the inker from normal (inking) position; mechanism constructed and arranged to be operative by the continued downward movement of the tripper toward abnormal (low) position to swing 65 the printer from normal (inking) position to printing position; resilient means constructed and arranged to effect simultaneously the swinging of the printer from printing position back toward normal (inking) position and to lift the tripper toward 70 normal (high) position; and resilient means arranged to effect simultaneously the movement of the inker back toward normal (inking) position and to continue the movement of the tripper back towards normal (high) 75 position.
9. A chromatic chase for printing machines, which comprises a color-inker located below type level, and mounted to be movable from normal (inking) position; a color-printer pivoted adjacent the color-inker to be oscillated from normal (inking) position in contact with the inker to printing position and back to inking position; a tripper mounted to be reciprocable from and 80 to normal position above type level in the press in the path of the impression surface thereof; yielding means constructed and arranged to tend to maintain said three elements in normal positions; and mechanism 85 controlled by said tripper whereby, upon the depression of the tripper, first the printer and the inking surface of the inker are separated sufficiently to free the path of oscillation of the printer from the presence of 90 the inker, and then and only then the printer is swung to printing position.
10. A chromatic chase for printing presses, which comprises a pivoted color-printer and a color-inker located adjacent it and normally contacting therewith; a tripper arranged to be operated by the impression surface of the printing press; means connected with the tripper for moving the inking surface of the inker directly away 100 from the printer; additional means connected with the tripper for swinging the printer to printing position; spring means compressed by the tripper and operating after the tripper is released from the 105 impression surface of the press, for swinging the printer from printing position back to inking position; and spring means compressed by the tripper and operating after the tripper is released from the impression 110 surface of the press, for moving the inker back into contact with the printer.
11. A chromatic chase for printing presses, which comprises a pivoted color-printer; a color-inker located adjacent it; a tripper arranged to be operated by the impression surface of the printing press; and mechanism operating between the tripper on one hand and the inker and printer respectively on the other hand, whereby the 115 movement of the tripper successively first separates the inker and printer and then moves the printer to printing position.
12. A chromatic chase for printing presses which comprises a pivoted color-printer, a 120
- 130

color inker normally inking the printer; a tripper arranged to be operated by the impression surface of the printing press; and mechanism constructed and arranged to be operated by the tripper first to move the inking surface of the inker directly away from the printer and then to move the printer to printing position.

13. A chromatic chase for printing presses which comprises a color-printer mounted to oscillate to and fro from a normal inking position below type level of the press to a horizontal printing position at type level; a color-inker located adjacent the color-printer and mounted to be movable from normal position in contact therewith and out of the path of movement thereof; a tripper constructed normally to project above type level in the path of the impression surface of the press; connecting means between the tripper and the color-inker arranged to cause the inker to be moved away from and out of the path of movement of the printer upon the depression of the tripper; and connecting means between the tripper and color-printer arranged to cause the printer to be swung from inking to printing position upon the depression of the tripper after said withdrawal of the inker.

14. A chromatic chase for printing presses which comprises a main frame; a color-printer mounted in said frame to oscillate to and fro from a normal inking position to a horizontal printing position at type level of the press; a color-inker mounted in said frame adjacent the color-printer and movable from normal position in contact with said printer to a position out of the path of movement of the printer; a tripper mounted in said frame and normally projecting above the same and above type level in the path of the impression surface of the press; connecting means between the tripper and the color-inker and arranged to cause depression of the tripper to move the inker away from the printer and out of its path of movement; and connecting means between the tripper and color-printer and arranged to cause the depression of the tripper to swing the printer from inking to printing position after said withdrawal of the inker.

15. A chromatic chase for printing presses which comprises a color-printer mounted to oscillate to and fro from a normal inking position below type level of the press to a horizontal printing position at type level; a color-inker located adjacent the color-printer and mounted to be movable from normal position in contact with the color-printer and out of the path of movement thereof; a tripper constructed normally to project above type level in the path of the impression surface of the press; and mechanism connected between the tripper on one hand and the printer and inker on the other, and

arranged to cause, successively, upon the depression of the tripper, the movement of the inker away from the printer out of its path of movement, and the swinging of the printer to printing position.

16. A chromatic chase for printing presses which comprises a color-printer mounted to oscillate to and fro from a normal inking position below type level of the press to a horizontal printing position at type level; a color-inker located adjacent the color-printer and mounted to be movable from normal position in contact with the color-printer and out of the path of movement thereof; a tripper constructed normally to project above type level in the path of the impression surface of the press; connecting means with the tripper whereby its initial downward movement moves the color-inker away from the printer and out of its path of movement; and connecting means whereby the further downward movement of the tripper moves the printer to printing position.

17. A chromatic chase for printing presses which comprises a color-printer mounted to oscillate to and fro from a normal inking position below type level of the press to a horizontal printing position at type level; a color-inker located adjacent the color-printer and mounted to be movable from normal position in contact therewith and out of the path of movement thereof; a tripper constructed normally to project above type level in the path of the impression surface of the press; and mechanism constructed and arranged to cause, successively, upon the depression of the tripper, the movement of the inker away from the printer out of the path of movement thereof, and the swinging of the printer to printing position, and to cause, upon withdrawal of the depressing force on the tripper, the successive return of printer and inker to normal positions.

18. A chromatic chase for printing presses which comprises a color-printer mounted to oscillate to and fro from a normal inking position below type level of the press to a horizontal printing position at type level; a color-inker located adjacent the color-printer and mounted to be movable from normal position in contact therewith and out of the path of movement thereof; a tripper constructed normally to project above type level in the path of the impression surface of the press; springs arranged to tend to hold the printer and inker in their normal inking relation; and mechanism operated by the depression of the tripper to move the inker and printer successively from their inking positions, and the inker out of the path of movement of the printer, said mechanism and said springs being arranged to cause such movement to

store energy in said springs, and to cause the springs to operate the mechanism to return the printer and inker successively to their inking positions.

- 5 19. A chromatic chase for printing machines, which comprises a color-printer and a color-inker mounted adjacent to one another; a tripper arranged to be depressed by the impression surface of the press; 10 mechanism connected to the tripper and operated by the initial depression thereof to separate the inker and printer prior to movement of the printer to printing position of rest; mechanism connected to the 15 tripper and operated by further depression thereof to move the printer to its printing position of rest; and spring means combined with the tripper and arranged to permit further and idle depression thereof 20 after the printer has reached its printing position of rest.

20. A chromatic chase for printing machines, which comprises an independently movable color printer and color inker; a tripper arranged to be depressed by the impression surface of the press; mechanical connections between the tripper and the printer and inker respectively and arranged to cause the tripper in its successive stages of depression first to move the inker away 25 from the printer and then move the printer to printing position; spring means combined with the tripper to permit further depression of the tripper after the printer has reached printing position; and spring 30 means compressed by the depression of the tripper and operating upon the release of the tripper from the impression surface of the press to cause the repetition in reverse order of the above specified movements of the 35 printer and inker.

JOHN A. WHITTINGTON.
